ABSTRACT: A method and apparatus for winding successively onto a plurality of spools a filamentary material, such as wire, which is continuously fed without interruption when the winding changes from one spool to another spool. A pair of spools are provided beside and parallel to each other with the winding taking place at any given instant on one of the spools. When this one spool has almost been filled the traverse which distributes the filamentary material along the spool is shifted from this one spool to the region of the empty spool while a deflecting roller is shifted to an operative position for deflecting the filamentary material into a loop around the empty spool. Each of the spools has, at an end, an auxiliary spool where a cutter cuts the filamentary material to terminate the length thereof which is wound onto the filled spool. The shifted deflecting roller is returned to its starting position so as to release the loop for movement onto the empty spool and the windings continue thereon. The operations are then repeated with the new spool after the previously empty spool has become almost filled.

METHOD AND APPARATUS FOR CONTINUOUSLY WINDING FILAMENTARY MATERIAL

BACKGROUND OF THE INVENTION

The present invention relates to a method and apparatus for winding filamentary material such as wire or the like onto spools.

While there are many already known methods and apparatus for winding filamentary material such as wire onto spools, all of these known methods and apparatus suffer from serious drawbacks. Thus, according to one known wire-reeling method and apparatus for continuously winding wire onto successive reels, as shown in U.S. Pat. No. 2,932,462, there is an overflow or overrunning of the wire from a spool or reel onto the empty spool which is next to be filled by means of a guide which moves back and forth and which is actuated by a relay in order to deflect the path of movement of the wire to the reel or spool onto which the wire starts to wind after a previous spool has been filled. With this method and apparatus the transfer from one spool which is filled to the next empty spool which is to be filled only takes place when the guide has moved beyond the end flange of the empty spool as well as the neighboring end flange of the filled spool. Aside from the fact that this known type of construction is exceedingly complex, it cannot be used for arrangements where spools are situated beside and parallel to each other and is only suitable for use with constructions where the several spools are coaxially arranged one after the other along a common axis.

It is also known, according to U.S. Pat. No. 2,341,369, to guide the wire which is to be wound onto a spool initially over a guide roller, then in part over the main spool, and then over a laterally arranged deflecting roller situated at the region of the plane of the adjacent flanges of coaxial primary and auxiliary spools with this deflecting roller having a plane inclined to the common plane of these end flanges. This deflecting roller is actuated by way of a suitable device so that it is swingable about an axis which extends across and intersects its rotary axis by a relatively sharp angle of approximately 90°, so that the wire which was initially guided over the deflecting roller onto the auxiliary spool, upon turning of the latter, will be directed thereby away from the deflecting roller exclusively onto the guiding roller from where it is distributed onto the main spool.

Devices of this type suffer from the disadvantage of requiring the complete filling of a single spool, after which the structure must be brought to a standstill while the starting end of the wire is first started onto the auxiliary spool and then brought onto the primary spool with the end of the wire being suitably fixed to the auxiliary spool, for example, so that with this type of method and apparatus a continuous movement of the filamentary material during winding thereof onto successive spools cannot be carried out.

It is accordingly a primary object of the invention to provide a method and apparatus which will enable continuous winding operations to go forward without interruption while a filamentary material such as wire is wound first onto one spool and then onto another spool which is situated beside and extends parallel to the one spool.

In particular, the present invention relates to a method and apparatus of this type which is capable of operating with a traverse which distributes the filamentary material along a given spool during the filling thereof and which then can be shifted to the empty spool to continue the operations with the latter.

Also, it is an object of the invention to provide a method and apparatus according to which it becomes possible to deflect the filamentary material during changeover from winding on a spool which is almost filled to winding on an empty spool in such a way that the winding operations can continue with the almost filled spool without any interruption while at the same time preparations are going forward to continue without interruption the winding of the filamentary material onto the empty spool.

Thus, it is an object of the invention to provide a method and apparatus which will enable a filamentary material such as wire to be continuously wound onto a plurality of spools of which at any given time one pair are situated beside and extend parallel to each other so that while the operations go forward with one spool, a previously filled spool can be removed and replaced by an empty spool on which the operations will be continued after filling of the previously empty spool.

In particular it is an object of the present invention to provide a method and apparatus which will enable all of these operations to take place without any interruption in the feeding of the filamentary material to the spools to be wound thereon.

Thus, it is an object of the invention to provide a method and apparatus which will retain all of the advantages which accrue in connection with winding onto individual spools such as, for example, the provision of an elongated and undamaged starting end of the winding, so that this latter end, when necessary, can be welded or otherwise fixed to an end of the wire from another spool to provide substantially continuous spool lengths from a plurality of spools.

Moreover, it is an object of the invention to provide a method and apparatus which will enable the speed of rotation of the spools to be relatively high, as contrasted with the speeds of rotation which can be achieved with known methods and apparatus, so that a greater output is achieved providing for a more economical operation of the entire installation.

SUMMARY OF THE INVENTION

In accordance with the invention the filamentary material such as wire is directed by the traverse carriage and the guide rollers thereon to the empty spool while the wire continues to be guided by suitable wire guide and deflecting members onto the spool which is almost filled. The shifting of the traverse to the region of the empty spool locates the filamentary material beneath a swingable roller and over a deflecting roller which extends parallel to the spools and is shifted beneath the filamentary material. Thus, when the swingable roller swings around it will engage the filamentary material and form a loop around deflecting roller which has been shifted from a given starting position to an operating position located beneath the filamentary material.

Each spool has an auxiliary spool extending beyond an end flange of the primary spool, and a flange of the auxiliary spool which is smaller than and distant from the common flange of the primary and auxiliary spools carries a cutting means into whose path of rotary movement the filamentary material is brought by the swingable roller. Through this cutting means the filamentary material is severed so that its winding onto the spool which has almost been filled will terminate and now the filamentary material is wound onto the auxiliary spool. This latter winding onto the auxiliary spool continues only until the shifted deflecting roller is returned to its starting position and now the filamentary material will, in a well-known manner, form a loop over the flange of the primary spool into the interior of the latter to be wound thereon.

In order to carry out the method of the invention it is of advantage to use, in accordance with the structure of the invention, a swingable arm which carries a swingable roller to swing the latter from its starting to its end position, with this end position being terminated by a limit switch actuated by the arm. Also, it is of advantage to arrange this swingable arm eccentrically with respect to the axis of the spool. Furthermore, it is of advantage to limit the auxiliary spool by a pair of end flanges one of which is an end flange in common with the primary spool and the other of which carries the cutting means. When dealing with a filamentary material such as wire, the cutting means does not carry out a slicing action but rather cuts in the manner of an anvil. The flange of the auxiliary spool which carries the cutting means has a diameter smaller than the common flange of the auxiliary and primary spools. This cutting means is preferably adjustable in a radial direction. FINALLY, it has proved to be of advantage if the

inner cylindrical cores of the auxiliary and primary spools not only are coaxial but also are of the same diameter.

BRIEF DESCRIPTION OF DRAWINGS

The invention is illustrated by way of example in the accompanying drawings which form part of this application and in which:

FIG. 1 is a schematic side elevation of the winding apparatus and method of the invention with a pair of parallel spools being shown in FIG. 1 with their axes extending perpendicular to the plane of FIG. 1;

FIGS. 2 is a top plan view schematically illustrating the structure of claim 1 and additional details;

FIG. 3 is a view corresponding to FIG. 1 and showing the operations and position of the parts during a phase of the spool changeover subsequent to that illustrated in FIGS. 1 and 2;

FIG. 4 is a schematic plan view of the parts and operations illustrated in FIG. 3;

FIG. 5 is an end view of the features illustrated in FIGS. 3 and 4, as seen from the left of FIGS. 3 and 4; and

FIG. 6 is a partly sectional schematic transverse view of the structure of FIG. 5 taken along the line VI-VI of FIG. 5 in the direction of the arrows.

DESCRIPTION OF A PREFERRED EMBODIMENT

The method and apparatus operate with a pair of parallel spools situated beside each other as illustrated in the drawings. These spools are supported for rotary movement in any suitable bearings on a machine frame 1, and the spools 2 and 3 are supported for rotary movement in such a way that their axis 4 and 5 are spaced from and parallel to each other. The spools are driven so as to be rotated about their axis to wind the filamentary material, such as wire or the like, thereon from any suitable well-known drive. As is apparent from the upper part of FIG. 1, the spool 2 is situated at the *a* side of the apparatus while the spool 3 is situated at the *b* side thereof. The drives which are operatively connected with the spools will, in a well-known manner, rotate the spool 2 in a clockwise direction and the spool 3 in a counterclockwise direction, as viewed in FIG. 1. These directions of rotation are also indicated by the arrows in FIG. 1.

A traverse carriage 6 is situated at an elevation higher than the spools for moving back and forth parallel to the axes thereof for distributing the wire in suitable convolutions onto the spools in even layers where the convolutions of the filamentary material are closely located one next to the other. Such traverse mechanisms are well known. In addition, however, the traverse 6 is capable of shifting from a location from one side coacting with one spool to a location at the other side for coacting with the other spool, and for this purpose the traverse mechanism 6 has a pair of reversing rollers the right one of which coacts with the filamentary material when the mechanism 6 is in the region of the spool 2 while the left roller coacts with the filamentary material to guide it to the spool 3, as indicated by the dotted line illustration of the traverse mechanism 6 in FIG. 1. The shifting of the traverse mechanism 6 from the *a* side to the *b* side and back again to the *a*, etc., is carried out in any suitable manner.

In the space between the pair of spools 2 and 3 there are wire-engaging components 7 and 8 horizontally shiftable in a direction parallel to the spool axis from the rest position shown for the component 7 in FIG. 4 to the operative position shown for the component 8 in FIG. 4. Thus, any suitable fluid under pressure can actuate a piston in a cylinder so as to hydraulically or pneumatically displace the wire-engaging guide components 7 or 8 between their rest and operative positions. The component 7 coacts with the spool 2 in the same way that the component 8 coacts with the spool 3.

In addition there are situated in the space between the pair of spools 2 and 3 a pair of wire deflecting rollers 9 and 10 respectively shiftable parallel to the direction of shifting of the

components 7 and 8 also by way of a suitable pneumatic or hydraulic structure, as is apparent from FIG. 4. In this case also the deflecting roller 9 coacts with the spool 2 in the same way that the deflecting roller 10 coacts with the spool 3. Additional wire-deflecting rods or the like 11 and 12 are situated between the pair of spools, and these components also coact respectively with the spools 2 and 3. The wire-guiding components 11 and 12 may remain stationary and extend vertically in contrast to the horizontal direction of shifting movement of the components 7 to 10. While components 7 and 8 may be in the form of rollers having vertical turning axis, the deflecting rollers 9 and 10 respectively have horizontal turning axis which are parallel to the axis of the spools 2 and 3.

A pair of rotary drums 15 and 16, eccentrically arranged with respect to spools 2 and 3, respectively, are situated in the region of the drive motors 13 and 14 which by suitable belt-and-pulley drives serve to rotate the drum 15 about its axis 21 which is parallel and spaced from the axis of the spool 2 and the drum 16 about its axis 22 which is parallel and spaced from the axis of the spool 3. These rotary drums 15 and 16 respectively fixedly carry radially extending arms 17 and 18. The free ends of these arms respectively support for free rotary movement swingable guide rolls 19 and 20, these rolls being swingable together with the arms 17 and 18 about the axis 21 and 22 respectively, the drums 15 and 16 are turned by actuation of the motors 13 and 14. Each of the rollers 19 and 20 is provided at its periphery with a groove of V-shaped configuration, for example, for reliably receiving and guiding the wire.

The arms 17 and 18 are shown in their starting positions in FIG. 1. In order to limit the swinging of these arms in clockwise and counterclockwise directions, respectively, as viewed in FIG. 1, suitable limit switches are provided. Thus, in association with each swingable roller 19 and 20 is a limit switch including a pair of stationary contacts K bridged by a bridging conductor Kb carried by each of the arms 17 and 18 and engaging and bridging the space between contacts K when each arm reaches its end position. The arm 17 is shown in its end position in dotted lines in FIG. 1 at the left thereof, as well as in FIG. 3 at the left thereof, and it will be noted that in this position the bridging member Kb bridges the space between and engages the left pair of contacts K for actuating the limit switch to terminate the operation of the motor 13 when the arms 17 reaches the end position shown at the lower left portion of FIG. 1. In the same way during counterclockwise swinging of the arm 18 its extent of swinging will be terminated by closing of the circuit between the contacts K at the right of FIG. 1 upon being bridged by the electrically conductive strip Kb carried by the arm 18 so that in this way this right limit switch serves to terminate the operation of motor 14.

Each of the main or primary spools 2 and 3 is provided with an auxiliary spool extending from an end of the primary or main spool. Thus, the main spool 2 has an auxiliary spool 23 coaxial therewith and extending as far as adjacent to the arm 17, and in the same way the spool 3 has an auxiliary spool 24 fixed to and extending coaxially therewith between the arm 18 and the end flange adjacent thereto. These end flanges of the spools which are adjacent to the arms 17 and 18 form flanges in common with the main and auxiliary spools. The auxiliary spools 23 and 24 are respectively provided with inner diameters, at their cylindrical cores, which are equal to the core diameters of the spools 2 and 3. However, the flanges 25 and 26 of the auxiliary spools are of a smaller diameter than the flanges of the main spools.

Each of these smaller flanges carries at its surface which is directed toward the main spool a cutting means in the form of a cutting blade which operates with an anvil type of cutting action. The cutting means 27 is schematically illustrated carried by the flange 25 while the cutting means 28 is schematically illustrated carried by the flange 26. As is apparent particularly from FIG. 6, each of the flanges is provided with a radially extending slot 29 forming part of an adjusting means for radially adjusting the position of each cutting means. Thus, in FIG. 6 it

is apparent that the cutting means 27 may be adjusted along the slot 29 between the solid and dotted line positions illustrated for the cutting means 27, for example. The anvil type of cutting blade 27 simply has an extension extending through the slot 29 and threaded to receive a nut capable of fixing the cutting means 27 at the selected radial distance from the axis 4 of the spool 2. In the same way it is possible to radially adjust the location of the cutting means 28 from the axis 5 of the spool 3.

The cutting means 27 coacts with an anvil 31 to cut through the wire, and a wire-engaging element 30 (FIG. 5) deflects the wire to locate it in the path of movement of the cutting components 27 and 31 to be cut thereby.

The above described structure of the invention operates, in accordance with the method of the invention, as follows:

As is particularly apparent from FIGS. 1 and 2, when the parts are in the condition illustrated, the spool 3 is almost filled. The path taken by the wire Dr is indicated by the solid relatively dark line in the drawings. Thus, the wire Dr coming from any suitable source is first guided around a guide roller of the traverse mechanism 6. This mechanism 6, when the spool 3 is almost completely filled, is shifted from side b to side a of the apparatus so that it will now be located at the upper left position shown in FIG. 1. This will result in the guiding of the wire around the right roller of the traverse mechanism 6, as viewed in FIG. 1, whereas the wire was guided around the left roller of the traverse mechanism when wound onto the spool 3 until the latter was almost completely filled.

From the traverse mechanism the wire Dr is deflected in the manner most clearly apparent from FIGS. 2 and 4 around the guide 8 which has been pneumatically or hydraulically displaced to its operative position in a direction parallel to the axes 4 and 5, and from the guide 8 the wire will be guided around the vertical guide 12 so as to continue to be wound onto the spool 3 without any interruption during the last or terminal phase of the winding of the wire onto the spool 3.

This guide 8 when shifted to its operative position serves to deflect the wire from the traverse mechanism 6 transversely across the end flange of the spool 2 which is in common with the auxiliary spool 23 to a location situated beneath the swingable guide roller 19. Thus, the guide 12 coacts with the deflecting roller 8 to prevent the wire from being displaced from the spool 3 during the terminal part of the winding of the wire onto the spool 3. During this phase of the operation 45 preparations are going forward, as described above and below, for starting the winding onto the spool 2 so that the winding of the wire will continue without interruption as will be apparent from the description below.

After the wire has thus been deflected by the component 8 to the position of FIG. 2 extending beneath the swingable guide roller 19, the deflecting roller 9 is pneumatically or hydraulically shifted from the position of FIG. 2 into the position of FIG. 4 where it becomes situated beneath the wire which in turn extends beneath the roller 19, so that now the wire which extends beyond the flange of spool 2, which is in common with spool 23, extends between the rollers 9 and 19.

The motor 13 is now actuated through any suitable control structure so as to swing the arm 17 in a clockwise direction, as viewed in FIGS. 1 and 3, up to the dotted line position shown at the lower left portions of FIGS. 1 and 3 where the limit switch K, Kb is closed to terminate the operation of the motor 13. Thus at this time the roller 19 will be displaced from the dotted illustration thereof shown in FIG. 3 to the solid line illustration thereof shown in FIG. 3. In this way the swingable guide roller 19 has engaged the wire in the grooved periphery of the roller 19 and has displaced the wire around the deflecting guide roller 9 to form a loop which extends around the roller 9, which has been shifted to its operative position, onto the auxiliary spool 23, as is particularly apparent from FIG. 4. Thus, the wire now extends around the roller 9 in a loop extending around the common flange of the spools 2 and 23. The wire moves beyond the guide roller 19 to the components 8 and 12 to continue to be guided onto the spool 3 during the

terminal phase of the winding thereon. This operation is particularly apparent from FIGS. 3 to 5. It is only to be noted that for the sake of clarity in the illustration the guide roller 20 carried by the arm 18 and shown in FIG. 3 has not been illustrated in FIG. 4. In this way it is possible to more clearly illustrate the path taken by the wire as it travels to the spool 3 during the terminal phase of the winding thereon to the spool 3.

As soon as the swingable roller 19 has reached its end position, as determined by the limiting switch K, Kb, the wire-engaging element 30 presses the wire into the path of movement of the anvil cutter 27 to be engaged thereby, and now this member 29 coacts with the steel-cutting component 31 for cutting through the wire, as is illustrated most clearly in FIG. 5. This will, of course, provide a free end for the wire so as to terminate the winding thereof onto the spool 3. At the same time the wire which continued to be fed around the traverse mechanism 6 will continue to wind onto the auxiliary spool 23 until the deflecting roller 9 has been returned in a direction opposite to that illustrated in FIG. 4 to its starting position. These operations can, for example, be controlled by unillustrated timing relays which control and determine the proper sequence of the operations.

The result of the retraction of the roller 9 back to its starting position is that a loop of wire will no longer be capable of forming around the roller 9 and around the flange which is common to the spool 2 of the auxiliary spool 23. Thus, the wire loop, which previously extended around this flange, falls and the normal winding of the wire on the primary spool 2 commences.

At this instant, the control structure actuates the motor 13 for returning the arm 17 and the roller 19 back to their starting positions illustrated in FIG. 1. At the same time the wire deflecting guide 8 is returned to its starting position. Now, the completely filled spool 3 can be removed and replaced by a new empty spool in a well-known manner.

When the spool 2 is almost filled all of the above operations are repeated in the reverse direction so as to take place with this new spool which replaces the previously filled spool 3, so that now the traverse mechanism 6 is shifted from the a side to the b side and in a completely analogous manner all of the above operations are repeated for the empty spool which is now situated at the location of the illustrated spool 3. Thus, without interruption in the feeding of the wire to the traverse mechanism and from the latter to the spools the wire is wound completely onto one spool, and then the winding is started on the adjoining spool in a fully automatic manner as described above.

I claim:

1. In the method for continuously winding elongated filamentary material, such as wire or the like, onto one of a pair of parallel spools which are situated beside each other while a traverse carriage distributes the elongated material along the axis of a rotary spool on which it is wound with deflector components situated beneath the traverse carriage for deflecting the elongated filamentary material, the steps of shifting the traverse carriage from a spool which is almost filled to the other spool which is empty and which is about to be filled, while guiding the filamentary material to continue the winding thereof onto the one spool which is almost filled, shifting a deflecting roller in the path of the filamentary material while simultaneously swinging the filamentary material around the shifted roller beneath the empty spool and across an end flange thereof to an auxiliary spool, cutting the filamentary material, shifting the deflecting roller back to its starting position away from the path of movement of the filamentary material, and continuing the winding of the filamentary material onto the auxiliary spool until the deflecting roller is shifted back to its starting position, so that the filamentary material will then again pass over the end flange of the empty spool to become wound thereon.

2. In an apparatus for winding filamentary material such as wire, during continuous movement thereof, first onto one spool and then onto another spool with the latter spools being

situated beside each other and having stationary parallel axes, a traverse means for distributing the filamentary material along one spool which is being filled, said traverse means being shiftable to the region of the other of said spools when said one spool has almost been completely filled, a guide means for guiding the filamentary material to the one spool to complete the filling thereof while the traverse means situates the filamentary material moving to said one spool in the region of the empty spool, said empty spool having beyond an end thereof an auxiliary spool coaxial with said empty spool, a deflecting roller means for engaging the filamentary material at the region of the empty spool, and swingable roller means swingable around the deflecting roller means to engage the filamentary material and directed it around said end flange of the main spool to the auxiliary spool, cutting means carried by said auxiliary spool for cutting the filamentary material to terminate the length of filamentary material which is wound on said one spool while the filamentary material now starts to wind onto the auxiliary spool, means for displacing said deflecting roller means into the path of the filamentary material and for returning said deflecting roller means back to its starting position to release the loop of filamentary material which extends around said deflecting roller means for movement back around the end flange of the empty spool onto the latter to be wound thereon, and said swingable roller means also returning to its starting position so that the winding operations will now continue with said traverse means at the empty spool while the latter becomes gradually filled so that the operations can then be repeated with respect to another empty spool which replaces the spool which has just been filled.

3. The combination of claim 2 and wherein a swingable arm carries said swingable roller means to swing the latter between starting and end positions.

4. The combination of claim 3 and wherein a limit switch means limits the extent of turning of said arm which carries said swingable roller means.
5. The combination of claim 4 and wherein said swingable arm has an axis of rotation which is parallel to but displaced from the axis of the empty spool which is about to be filled so that the swingable arm turns eccentrically with respect to the empty spool.
6. The combination of claim 5 and wherein said auxiliary spool has one end flange in common with the empty spool and distant from the latter another end flange, and said other end flange carrying said cutting means for cutting the filamentary material which is directed onto the empty spool.
- 10 7. The combination of claim 6 and wherein said flange of said auxiliary spool has a smaller diameter than the end flange of said empty spool which is common to the latter and said auxiliary spool.
- 20 8. The combination of claim 7 and wherein an adjusting means coacts with said cutting means for adjusting the latter radially with respect to said auxiliary spool along the flange of the latter which is distant from the common flange.
- 25 9. The combination of claim 8 and wherein said auxiliary and empty spools both have cores of the same diameter.
10. The combination of claim 9 and wherein the spool which has just been filled is identical with the empty spool which is about to be filled and also has an auxiliary spool extending from an end thereof, and all of the structure of said empty spool and the controls coacting therewith being duplicated for the other spool so that when the empty spool has almost been filled all of the operations can be repeated in the reverse direction with a new spool which replaces the filled spool.
